[57] **CLAIM**

The ornamental design for a convertible shoe box and display platform, as shown and described.

DESCRIPTION

FIG. 1 is a perspective view of the convertible shoe box and display platform according to the present invention, shown in its enclosed shoe box configuration;

FIG. 2 is a top view of the convertible shoe box and display platform shown in FIG. 1;

FIG. 3 is a bottom view of the convertible shoe box and display platform shown in FIG. 1;

FIG. 4 is a side view of the convertible shoe box and display platform shown in FIG. 1;

FIG. 5 is a front view of the convertible shoe box and display platform shown in FIG. 1;

FIG. 6 is a back view of the convertible shoe box and display platform shown in FIG. 1;

FIG. 7 is a top view of the convertible shoe box and display platform according to the present invention, shown in its display platform configuration;

FIG. 8 is a bottom view of the convertible shoe box and display platform shown in FIG. 8;

FIG. 9 is a side view of the convertible shoe box and display platform shown in FIG. 8;

FIG. 10 is a front view of the convertible shoe box and display platform in FIG. 8;

FIG. 11 is a back view of the convertible shoe box and display platform shown in FIG. 8;

FIG. 12 is an interior, top view of the lid portion of the convertible shoe box and display platform according to the present invention, with opposing tab elements shown extending inwardly; and,

FIG. 13 is a side view of the lid portion shown in FIG. 12.
